UNITED STATES PATENT OFFICE

BERNHARD HASENSTAB, OF BUFFALO, NEW YORK, ASSIGNOR TO MARKEL ELECTRIC PRODUCTS, INC., OF BUFFALO, NEW YORK, A CORPORATION OF NEW YORK

DESIGN FOR AN ELECTRIC-LIGHT CEILING FIXTURE

Application filed November 2, 1929. Serial No. 33,268. Term of patent 3½ years.

To all whom it may concern:

Be it known that I, BERNHARD HASENSTAB, a citizen of the United States, residing at Buffalo, in the county of Erie and State of New York, have invented a new, original, and ornamental Design for an Electric-Light Ceiling Fixture, of which the following is a specification, reference being had to the accompanying drawing, forming part thereof.

In said drawing:

Figure 1 is an elevation of an electric light ceiling fixture embodying my new design; in this figure half of the fixture is shown complete in full lines and the other half which

involves repetition of the pattern is indicated in marginal outline by dot and dash lines.

Figure 2 is a bottom plan view of the same, a segment comprising one-fifth of the area of the fixture being shown completely in full lines, the remainder of the fixture involving repetition of the pattern shown in this segment and being indicated in marginal outline by dot and dash lines.

I claim:

The ornamental design for an electric light ceiling fixture, substantially as shown and described.

BERNHARD HASENSTAB.
